IGNITER FOR GAS BURNERS

Oscar J. Leins, Milwaukee, Wis., assignor to Milwaukee Gas Specialty Company, Milwaukee, Wis., a corporation of Wisconsin

Application July 28, 1930, Serial No. 471,180

8 Claims. (Cl. 158—115)

My invention relates to igniters for gas burners and contemplates an improvement to guard against the escape of unburned gas from the burner in the event that the flame is quenched by liquid boiling over the sides of a vessel placed over the burner.

It is well known that, in the use of gas ranges, a burner flame is sometimes quenched by liquid boiling over the sides of a vessel on the range, entailing the escape of large quantities of gas where the range is, for the time being, unattended.

The instant invention is in the nature of an improvement on the lighting device illustrated and described in United States Letters Patent No. 1,747,015, issued February 11, 1930.

The instant invention provides means for automatically reigniting the gas issuing from the burner in cases where the flame is extinguished as above pointed out.

My invention is illustrated in the accompanying drawing in which:—

Figure 1 is a plan view of an arrangement embodying my invention, and Figure 2 is a partial sectional view taken on the line 2—2 of Figure 1, looking in the direction indicated by the arrows.

The usual gas manifold is illustrated at 3. The gas burner is illustrated at 4, this burner being fed from the manifold 3 by the usual feed pipe 5, to which air is admitted, in the usual way, at the end nearest the manifold. Gaseous fuel is lead into the feed pipe 5 by way of the nozzle pipe 6, from manifold 3, in which nozzle pipe the usual gas cock 7 is provided.

An igniter is provided in appropriate proximity to the burner 4. This igniter comprises a tube 8 leading from the manifold 3 and terminating in a torch head 9 an appropriate distance from the burner 4. Although only one burner is shown, it is, of course, understood that gas ranges embody a number of burners, usually four, and the torch head 9 is disposed centrally within these circularly arranged burners. A protecting hood 10 is mounted over the torch head 9 upon a flanged perforated collar 12 supported on the upcurved end of the tube 8, as shown in Figure 2, below the torch head. The hood 10 has the flue 11, opening at the top, and four openings 13, 13 in the circular side wall, each in line with the respective burner on the range. A tube 14 leads from each opening 13 toward the respective burner, as illustrated, each of these tubes having the longitudinally slot 14' at the bottom thereof to provide for the entry of air. As illustrated, each

of the tubes 14, 14 extends a short distance into the hood 10 and its inner end at the top is provided with an ear 14² in clamping engagement with the flue member 11, the upper end of which, in turn, is in clamping engagement with the top 5 of the hood.

The torch head 9 has a pilot flame opening 16 and is fed by way of the tube 8 from the manifold 3, a coupling 15 being provided. This type of coupling is shown in Patent 1,747,015 and detailed 10 description here is unnecessary. Suffice it to say, for present purposes, that this coupling has a constant by-pass, adjustable by the valve screw 15', by which arrangement a constant pilot light is maintained at the opening 16.

Extending from the burner 4 toward the respective adjacent tube 14 is a small tube 16' which carries at its end the torch head 17 extending upwardly into the respective tube 14, as illustrated. This torch head has the port 18 drilled in the 20 side thereof and so positioned as to be directed toward the burner 4, and the port 19 drilled in the opposite side thereof and so positioned as to be directed toward the pilot flame at 16.

When a burner 4 is to be ignited, the cock 7 25 associated with that burner is open and gas enters the burner ready to be ignited at the burner openings 4', 4'. Gas also passes through the tube 16' to the torch head 17 issuing therefrom in both directions, one stream of gas from the port 18 30 toward and over the burner 4 and the other stream of gas through the port 19 toward and to the pilot flame at 16. The gas issuing from the port 19 in the torch head 17 into the tube flows toward the torch head 9 and is ignited by 35 the pilot flame. The flame is then conveyed back to the torch head 17 and to the stream of gas issuing from the port 18, thus causing a flame to be projected over the burner 4 to ignite the gas issuing from burner openings 4'. The gas 40 issuing from the torch head 17 remains ignited so long as the gas cock 7 is open and the continuing flame at 18 is essential to the instant invention as will now be pointed out.

It will be clear that the initial projection of 45 the flame at 18 is due to the initial rush of gas into the burner 4, and before the pressure thereof is relieved by the issue of gas through the burner openings 4'. By the time the pressure is thus relieved, however, the gas issuing from the burner 50 openings 4', or enough of them to light the others, is ignited and the flame at 18 then subsides to appropriate pilot proportions.

In the event that liquid, boiling over the sides of a vessel disposed over the burner, falls upon 55

the burner, and quenches the flame thereon, it does so just to the extent that the liquid fills the burner openings 4'. Just to the extent that burner openings 4' are closed the pressure within the burner is increased. This increase in pressure causes the projection of the flame from the port 18, over the burner, as indicated in Figure 2, and as soon as the filled burner openings become cleared by the evaporation of the liquid therein, the gas issuing therefrom is ignited by this temporarily projected flame. As such reignition takes place, the gas pressure within the burner is obviously gradually restored and, accordingly, the flame at 18 gradually recedes to resume appropriate pilot proportions. Obviously, except for this automatic reignition, the gas which would issue from the cleared burner openings 4' would be unignited, entailing the danger hereinabove referred to. It will be noted that torch head 17 is protected by tube 14 against quenching.

I claim:

1. In combination, a gas burner, means for maintaining a constant pilot flame, a torch head spaced laterally of said burner, a conduit supporting said head and fed from said burner, said head having two ports, one directed toward said burner and one directed toward said pilot flame, and means for directing gas from the port directed toward the pilot flame to said pilot flame and the flame back from said pilot flame to said torch head, said means shielding said torch head.
2. In combination, a gas burner, means for maintaining a constant pilot flame, a tube between said burner and said pilot flame, and a torch head extending vertically into said tube at a point spaced laterally of said burner intermediate the ends of said tube, a conduit secured to said burner supporting said head and fed from said burner, said torch head having two ports, one directed toward said burner and one directed toward said pilot flame.

3. In combination, a gas burner, means for maintaining a constant pilot flame, a tube between said burner and said pilot flame, said tube having a slot in the bottom thereof for the entry of air, and a torch head extending into said tube and supported laterally of said burner by a conduit extending outwardly of and fed from said burner, said torch head having two ports, one directed toward said pilot flame and one directed toward said burner.

4. In combination, a gas burner, a torch head for maintaining a pilot flame, a hood over said torch head, a tube carried by said hood and terminating short of said burner, and a second torch head extending vertically into said tube intermediate its ends and fed from said burner, said second torch head having a port directed toward

said burner and having additional means for feeding gas to said tube.

5. In combination, a gas burner, means for maintaining a pilot flame in proximity to said burner, a torch head, and means for supplying gas from the interior of said burner to said torch head including a conduit extending from the side wall of said burner and spacing said torch head from said burner, said torch head having two opposed lateral ports to direct streams of gas simultaneously one over said burner and the other to said pilot flame.

6. In combination, a gas burner, a pilot light in appropriate proximity thereto, a port in said pilot light for maintaining a pilot flame, a hood for said pilot light having a lateral opening directed toward said burner, a tube secured to said hood and leading from said opening toward said burner, said tube terminating short of said burner, a torch head associated with said burner and positioned in said tube intermediate its ends, said head having a pair of oppositely disposed ports, one port being directed toward said burner, the other port being directed toward said pilot light.

7. In combination, a gas burner, a pilot light in appropriate proximity thereto, a port in said pilot light for maintaining a pilot flame, a hood for said pilot light having an opening therein directed toward said burner, a tube secured to said hood and leading from said opening toward said burner, flue means disposed within said hood for causing a flow of fresh air through said tube, a torch head positioned near the outer extremity of said tube, said torch head having a pair of oppositely disposed ports projecting into and protected by said tube, and a conduit communicating with the interior of said burner at one end and extending laterally outwardly of said burner toward said pilot light, said torch head being supported on the opposite end of said conduit and fed thereby from said burner.

8. In combination, a gas burner, a pilot light in proximity thereto, a port in said pilot light, a gas supply conduit supporting said pilot light, a hood positioned over said light and secured to said conduit, said hood having an opening therein directed toward said burner, a tube secured to said hood and leading from said opening toward said burner, and a torch head spaced from said burner and extending vertically into said tube intermediate its ends, and a conduit extending outwardly from the side wall of said burner for supporting said torch head laterally of said burner, said torch head being provided with a pair of laterally disposed ports directed oppositely in said tube for transmitting a flame from said pilot light to said burner.

OSCAR J. LEINS.
